DESIGN FOR A TEMPLET FOR FACILITATING THE DRAWING OF GEOMETRICAL PATTERNS

James McKenna, Lisburn, Ireland

Application November 28, 1933. Serial No. 49,887

Term of patent 7 years

To all whom it may concern:

Be it known that I, JAMES MCKENNA, a subject of the King of Great Britain and Ireland, and a resident of Lisburn, County Antrim, Ireland, have invented a new, original, and ornamental Design for a Templet for Facilitating the Drawing of Geometrical Patterns, of which the following is a specification, reference being had to the accompanying drawing, forming part thereof.

The figure is a plan view of a templet for facili-

tating the drawing of geometrical patterns, showing my new design, the same being of negligible thickness.

I claim:—

The ornamental design for a templet for facilitating the drawing of geometrical patterns, as shown and described.

In testimony whereof I have affixed my signature hereto this 24th day of November, 1933.

JAMES MCKENNA.
